UNITED STATES PATENT OFFICE.

WILLIAM F. GROENE, OF CINCINNATI, OHIO, ASSIGNOR TO THE R. K. LE BLOND
MACHINE TOOL COMPANY, OF CINCINNATI, OHIO, A CORPORATION OF OHIO.

TAILSTOCK.

1,361,792.

Specification of Letters Patent. Patented Dec. 7, 1920.

Application filed September 22, 1919. Serial No. 325,297.

To all whom it may concern:

Be it known that I, WILLIAM F. GROENE, a citizen of the United States, residing at Cincinnati, in the county of Hamilton and State of Ohio, have invented an Improvement in Tailstocks, of which the following description, in connection with the accompanying drawings, is a specification, like characters on the drawings representing like parts.

The invention to be hereinafter described relates to tail stocks for lathes and other machine tools, and more particularly to improved means for adjusting and securing the dead spindle of the tail stock.

In the use of tail stocks as heretofore constructed, considerable care must be exercised in adjusting the dead center into engagement with the work with the correct amount of pressure. If the center is forced in too tightly, rotation of the work with respect to the tail stock is liable to develop heat sufficient to burn and injure the center. On the other hand, if the center is adjusted into too loose engagement with the work, the operations on the latter will not be accurately performed. Therefore, considerable judgment has been necessary in adjusting the center with the proper pressure against the work, and there is always a chance that the correct adjustment will not be obtained.

One of the purposes of the present invention, therefore, is to provide means for adjusting the center into engagement with the work with provision for automatically obtaining the proper pressure without requiring attention on the part of the operator. As a consequence, the center may be quickly adjusted into engagement with the work without danger of burning the center or permitting lost motion between the center and the work which would prevent accurate operations on the work.

Another purpose of the invention is to provide means for automatically clamping or securing the dead center spindle after it has been given the proper axial adjustment.

Another purpose of the invention is to provide means for imparting the proper axial adjustment to the dead center spindle, and to secure the spindle in different positions of adjustment, all under the control of a single operating handle, the construction being such that the adjustment and

securing operations are progressively performed and the securing operation is properly timed with respect to the adjusting operation.

With the aforesaid and other objects in view, the character of the invention will be best understood by reference to the following description of one good form thereof shown in the accompanying drawings, wherein:

Figure 1 is a view partly in elevation and partly in section of a tail stock embodying the invention; and

Fig. 2 is a plan of the tail stock shown in Fig. 1, certain parts thereof being shown in section.

Referring to the drawings, 1 designates a support which may be the bed of a lathe or other machine tool, and 2 designates the body of the tail stock provided with a dove-tail base 3 adapted to slide in either of a pair of dove-tail grooves 5 on said support. The dove-tail 3 may be provided with a gib 7 connected to screws 9 and 11 projecting through bores in the body 2, said screws being provided with adjusting nuts 13 and 15. The construction is such that the nuts may be tightened to press the gib against one of the inclined walls of the dove-tail groove and thereby secure the body in different positions of adjustment on the support.

At the upper end of the body 2 is a boss or rounded portion 17 having a bore in which is mounted the dead spindle, in the present instance, in the form of a sleeve 19. A center 21 has a tapered head 23 for engagement with the work, and a tapered shank 25 adapted to be set with a tight friction fit in the sleeve spindle 19. A draw bolt 27 is mounted in a counterbore in the spindle sleeve, and is confined against axial movement with respect to the boss 17 by a cap 29 having a collar 31 threaded to said boss. The inner end of the draw bolt has a head 33 adapted to engage the inner end of the center and release the same from the spindle on adjustment of the latter a sufficient distance toward the right of Fig. 2.

Suitable means may be provided for imparting the axial movement to the spindle. To accomplish this, in the present instance, the spindle is provided with a rack 35 meshing with a gear 37 mounted in a bore in the head extending transversely to the spindle receiving bore referred to. The gear

37 is formed or secured on a sleeve shaft 39 projecting upwardly therefrom and beyond the upper end of the head, where it is provided with a collar 41 for engagement 5 with the upper end of the head to confine the sleeve shaft against downward axial movement. Projecting laterally from the collar 41 and preferably integral therewith is a socket 43 containing a plunger 45 (Fig. 10 2 urged outwardly by a coil spring 47 in said socket confined between said plunger and a screw plug 49 threaded into said socket, said plug being adjustable to vary the tension of the spring as desired. 15 An operating member or handle 51 is provided with a hub 53 threaded to a screw portion 55 of a stud shaft 57 projecting downward through the sleeve shaft 39 and beyond the gear 37. A toe or lug 59 (Fig. 20 2) projects from the handle hub 53 and is adapted to engage the spring-pressed plunger 45.

The construction is such that when the handle 51 is rotated in a clockwise direction 25 (Fig. 2), the toe 59 will press against the plunger 45 and through the coil spring 47, and the socket 43 will yieldingly impart rotative motion to the sleeve shaft 39 and the gear 37. Since the latter meshes with the 30 rack 35, it will serve to adjust the dead spindle axially. The spindle will be moved until its center comes into engagement with and is arrested by the work. Thereupon, any further movement of the handle will merely 35 compress the coil spring without transmitting further movement to the spindle. The arrest of the spindle by engagement with the work may be readily sensed by the operator from the somewhat increased resistance to the movement of the handle caused 40 by the compression of the spring.

It is desirable to provide means for locking the gear 37 against rotation after the spindle center had been adjusted into proper 45 engagement with the work as described, and before the spindle is secured in its position of adjustment. To accomplish this, in the present instance of the invention, the stud shaft 57 is connected to the sleeve shaft 39 50 by a spline 61, so that the two shafts will rotate together, but the stud shaft may move axially with respect to the sleeve shaft. Splined to the lower end of the stud shaft is a tapered ring 63 adapted to fit into the 55 tapered bore of a bushing 65 secured in the bore or bearing receiving the gear 37 and at a point directly beneath the latter. The tapered ring 63 may be secured to the stud shaft 57 by a nut 67 threaded on a reduced 60 end of said shaft and bearing against the lower end of the ring.

The construction is such that after the spindle has been adjusted and arrested by engagement of the center with the work, the 65 handle may turn somewhat further owing to

the yield of the coil spring, thereby causing the threaded handle hub to act on the screw portion 55 of the stud shaft and draw the latter upward axially. This will jam the tapered ring 63 into tight engagement with 70 the tapered bore of the bushing 65, and thereby prevent rotation of the gear 37.

After the gear has been locked against rotation as described, it is desirable to clamp or secure the spindle in its bearing. To accomplish this, in the present instance, the upper end portion of the head 2 may be split by a kerf 69 extending horizontally inward to the bearing on a plane transverse to the axis of the stud shaft 57. The construction 80 is such that the handle may be turned somewhat after securing the gear against rotation, thereby screwing the handle hub farther down on the screw portion 55 of the stud shaft, and since said hub engages the 85 flange of the sleeve shaft resting on one end of the bearing for the sleeve shaft and the tapered ring presses against the bushing which engages the opposite end of said bearing, this further movement of the handle 90 will serve to press the portions of the head adjacent the kerf 69 toward each other and thereby contract the spindle bearing tightly to secure the spindle in its position of adjustment. 95

Thus, it will be seen that the same handle may serve first, to adjust the spindle to bring its center into proper engagement with the work, second, to lock the spindle adjusting gear against rotation, and third, 100 to contract the spindle bearing to secure the spindle in its position of adjustment, and these results are accomplished, in the present instance, by progressive movements of the handle in the same direction of rotation. 105 The gear locking device will automatically take effect when the spindle center has been arrested by proper engagement with the work, and the securing means for the spindle will automatically take effect after the 110 gear has been locked against rotation, all without requiring attention on the part of the operator.

When it is desired to retract the spindle center from the work, the handle is turned 115 somewhat in a contra-clockwise direction (Fig. 2). This will allow the bearing for the spindle to expand somewhat sufficiently to release the spindle owing to the inherent resilience of the metal forming the bearing. 120 This movement of the handle will cause the handle hub to unscrew somewhat from the screw portion 55 of the stud shaft, but the pitch of the ring 63 and bore of the bushing 65 is such that this movement of the 125 handle will not release the ring from the bushing, and therefore, will not permit rotation of the gear until after the spindle has been released. Further movement of the handle will cause the same to engage the 130

socket 43 and through the latter the sleeve shaft will be positively turned somewhat, and since the stud shaft is splined to the sleeve shaft and the ring is splined to the 5 stud shaft, the ring will be turned relatively to the bushing sufficiently to release the ring therefrom. Then further rotation of the handle will rotate the gear, and the latter meshing with the rack will serve to retract 10 the spindle the distance desired. Thus, the handle when turned in a contra-clockwise direction will serve first, to unclamp the spindle, second, to release the gear locking device, and third, to rotate the gear to adjust 15 just the spindle, and the change from one operation to another will be automatically made without requiring attention on the part of the operator.

It may be desirable to vary the pressure 20 of the spindle center against the work. This may readily be accomplished by adjustment of the screw plug 49 to vary the tension of the coil spring 47.

By my invention, a simple and efficient 25 device is provided whereby the spindle center may be quickly and readily adjusted into proper engagement with the work so as to prevent any possibility of burning of the center or too loose engagement of the center 30 with the work so as to result in imperfect work, and the center may be quickly and readily retracted from the work as desired.

It will be understood that the invention 35 is not limited to the specific embodiment shown, and that various deviations may be made therefrom without departing from the spirit and scope of the appended claims.

What is claimed is:—

1. A tail stock comprising a head having 40 a bore therein, a dead spindle movable axially in said bore, a rack on said spindle, a sleeve shaft rotatably mounted in said head, a gear fixed on said sleeve shaft meshing with said rack, an inner stud shaft within 45 the sleeve shaft and non-rotatably secured thereto, an operating member rotatable independently of the sleeve shaft, and means including a spring between the operating member and sleeve shaft yieldingly to transmit 50 motion from said operating member to said sleeve shaft.

2. A tail stock comprising a head having a bore therein, a dead spindle movable axially in said bore, a sleeve shaft mounted in 55 said head, an inner stud shaft mounted in said sleeve shaft and movable axially of the sleeve shaft, an operating member rotatably mounted on said inner shaft, a spring to transmit rotary movement from said operating member to said sleeve shaft, and operating connections between the sleeve shaft and spindle.

3. A tail stock comprising a head having 60 a bearing, a dead spindle mounted for longitudinal movement in the bearing and having

a rack, a sleeve shaft, a gear secured to the sleeve shaft and engaging the rack, a stud shaft extending through the sleeve shaft and movable axially relative thereto, a handle mounted for rotative movement on the stud 70 shaft, a spring for transmitting rotary movement of the handle to the sleeve shaft, and connections between the stud shaft and handle for locking the sleeve shaft.

4. A tail stock comprising a head having 75 a bearing, a spindle mounted for longitudinal movement in the bearing, a rack and pinion for moving the spindle longitudinally, a locking device for locking the pinion, a securing device for securing the spindle in 80 different positions of adjustment, a handle, and connections between the handle, the pinion, and securing devices for progressively operating the pinion, locking the pinion, and securing the spindle. 85

5. In a device of the class described, the combination of a spindle having a rack, a pinion for advancing and retracting the spindle, a sleeve shaft to which the pinion is secured, a handle having a projection 90 adapted to engage a part carried by the sleeve shaft for rotating the sleeve shaft and pinion, and yielding devices between the projection on the handle and part on the sleeve shaft for yieldingly advancing the 95 spindle.

6. In a tail stock, the combination of a spindle having rack teeth, a sleeve shaft carrying a pinion meshing with the rack teeth, a stud shaft, a handle rotatably 100 mounted on the stud shaft and having a projection, a spring between the projection and sleeve shaft for yieldingly rotating the latter from the handle, and a threaded connection between the handle and stud shaft for 105 locking the sleeve shaft and pinion.

7. A tail stock comprising a head having a bore therein, a dead spindle mounted in said bore, a pair of shafts one within the other and mounted for independent rotary 110 movements, a gear on one of said shafts, a rack on said spindle meshing with said gear, a handle mounted on the other of said shafts, means to transmit rotary motion from the handle to the shaft carrying the gear axially 115 to slide said spindle, securing means for said spindle, and means to transmit axial movement from the handle to its shaft to render the securing means effective.

8. A tail stock comprising a head having 120 a bore therein, a dead spindle mounted in said bore, a rack for said spindle, a sleeve shaft having a gear thereon meshing with said rack, a shaft rotative with but movable axially in said sleeve shaft, a handle on said 125 axially movable shaft, a conical seat in said head, a conical member on the axially movable shaft for engagement with said seat, and spring means yieldingly to impart rotary movement from said handle to said 130

- 4
1. A sleeve shaft axially to move said spindle, said handle having a hub threaded on said axially movable shaft for adjusting the latter to tighten the conical member into the 5 conical seat, to prevent rotation of said shafts and to draw portions of said head into clamping relation with said spindle.
2. A tail stock comprising a head having a split bearing, a spindle mounted in said 10 bearing, and means including a handle for shifting said spindle axially in said bearing until limited by engagement with a piece of work and then automatically acting by further movement of the handles for contracting 15 said split bearing into secure gripping relation with said spindle.
3. A tail stock comprising a head having a split bearing, a spindle mounted in said bearing, a sleeve shaft, means to transmit 20 motion from said sleeve shaft to said spindle to slide the latter axially in said bearing, a clamp shaft projecting through said sleeve transversely to said bearing, and a handle and yielding connections for rotating said 25 sleeve shaft to slide said spindle and for axially adjusting said clamp shaft to contract said split bearing into secure gripping relation with said spindle.
4. A tail stock comprising a head having a split bearing, a spindle mounted in said bearing, a sleeve shaft, a clamp shaft mounted in said sleeve shaft, devices on said 30 sleeve shaft and clamp shaft for contracting said bearing tightly to said spindle on relative axial adjustment of said shafts, means for transmitting movement from said 35 sleeve shaft to said spindle axially to adjust the latter, a handle, means to impart rotary movement from said handle to said sleeve 40 shaft, and means actuated by said handle to produce the relative axial adjustment of said shafts for clamping the bearing to the spindle.
5. A tail stock comprising a head having a split bearing, a spindle mounted in said bearing, a device for adjusting said spindle axially in said bearing, a securing device for contracting said bearing to secure the spindle in different positions of adjustment, an 45 operating handle and connections between said handle and said adjusting and securing devices for progressively rendering the same effective in the order named on movement of said handle.
6. A tail stock comprising a head having a split bearing, a spindle mounted in said bearing, a device for adjusting said spindle axially in said bearing, a locking device for said adjusting device, a securing device for contracting said bearing to secure the spindle in different positions of adjustment, a handle, and connections between said handle and devices for progressively rendering the same effective in the order named.
7. A tail stock comprising a head having a split bearing, a spindle mounted in said bearing, a device for adjusting said spindle axially in said bearing, a locking device for said adjusting device, a securing device for contracting said bearing to secure said spindle in different positions of adjustment, a handle, connections between said handle and devices for progressively rendering the same effective in the order named.
8. A tail stock comprising a head having a split bearing, a spindle mounted in said bearing, a device for adjusting said spindle axially in said bearing, a locking device for said adjusting device, a securing device for contracting said bearing to secure said spindle in different positions of adjustment, a handle, connections between said handle and devices for progressively rendering the same effective in the order named.
9. A tail stock comprising a head having a split bearing, a spindle mounted in said bearing, a device for adjusting said spindle axially in said bearing, a locking device for said adjusting device, a securing device for contracting said bearing to secure said spindle in different positions of adjustment, a handle, connections between said handle and devices for progressively rendering the same effective in the order named.
10. A tail stock comprising a head having a split bearing, a spindle mounted in said bearing, a sleeve shaft, means to transmit motion from said sleeve shaft to said spindle to slide the latter axially in said bearing, a clamp shaft projecting through said sleeve transversely to said bearing, and a handle and yielding connections for rotating said sleeve shaft to slide said spindle and for axially adjusting said clamp shaft to contract said split bearing into secure gripping relation with said spindle.
11. A tail stock comprising a head having a split bearing, a spindle mounted in said bearing, a sleeve shaft, a clamp shaft mounted in said sleeve shaft, devices on said sleeve shaft and clamp shaft for contracting said bearing tightly to said spindle on relative axial adjustment of said shafts, means for transmitting movement from said sleeve shaft to said spindle axially to adjust the latter, a handle, means to impart rotary movement from said handle to said sleeve shaft, and means actuated by said handle to produce the relative axial adjustment of said shafts for clamping the bearing to the spindle.
12. A tail stock comprising a head having a split bearing, a spindle mounted in said bearing, a device for adjusting said spindle axially in said bearing, a securing device for contracting said bearing to secure the spindle in different positions of adjustment, an operating handle and connections between said handle and said adjusting and securing devices for progressively rendering the same effective in the order named on movement of said handle.
13. A tail stock comprising a head having a split bearing, a spindle mounted in said bearing, a device for adjusting said spindle axially in said bearing, a locking device for said adjusting device, a securing device for contracting said bearing to secure the spindle in different positions of adjustment, a handle, and connections between said handle and devices for progressively rendering the same effective in the order named.
14. A tail stock comprising a head having a split bearing, a spindle mounted in said bearing, a device for adjusting said spindle axially in said bearing, a locking device for said adjusting device, a securing device for contracting said bearing to secure said spindle in different positions of adjustment, a handle, connections between said handle and devices for progressively rendering the same effective in the order named.
15. A tail stock comprising a head having a bearing therein, a spindle mounted in said bearing, means including a spring for moving said spindle axially into engagement with a piece of work, and means for varying the compressing tension of said spring for adjustably determining the pressure of the spindle against the work.
16. A tail stock comprising a head having a split portion with a bore therein, a dead spindle mounted in said bore and having a rack, a gear meshing with said rack, a sleeve projecting from said gear and having a socket therein, a spring-pressed plunger mounted in said socket, a stud in said sleeve having a tapered element at one end thereof, a handle having a hub threaded on said stud and a member projecting from said hub to engage said spring-pressed plunger and turn said gear to advance said rack and spindle on a preliminary movement of said handle and to screw said hub down on said stud and press the split portion of the head tightly to said spindle on further movement of said handle.
17. In testimony whereof, I have signed my name to this specification.

WILLIAM F. GROENE.
